(57) **CLAIM**

The ornamental design for a mounting hardware, as shown and described.

DESCRIPTION

FIG. 1 is an upper perspective view of an embodiment of a mounting hardware, illustrating the mounting hardware mounted to exemplary environment;

FIG. 2 is another upper perspective view of the mounting hardware shown in FIG. 1;

FIG. 3 is a lower perspective view of the mounting hardware shown in FIG. 2;

FIG. 4 is a front view of the mounting hardware shown in FIG. 2;

FIG. 5 is a rear view of the mounting hardware shown in FIG. 2;

FIG. 6 is a left-side view of the mounting hardware shown in FIG. 2;

FIG. 7 is a right-side view of the mounting hardware shown in FIG. 2;

FIG. 8 is a top view of the mounting hardware shown in FIG. 2;

FIG. 9 is a bottom view of the mounting hardware shown in FIG. 2;

FIG. 10 is an upper perspective view of another embodiment of a mounting hardware, illustrating the mounting hardware mounted to exemplary environment;

FIG. 11 is another upper perspective view of the mounting hardware shown in FIG. 10;

FIG. 12 is a lower perspective view of the mounting hardware shown in FIG. 11;

FIG. 13 is a front view of the mounting hardware shown in FIG. 11;

FIG. 14 is a rear view of the mounting hardware shown in FIG. 11;

FIG. 15 is a left-side view of the mounting hardware shown in FIG. 11;

FIG. 16 is a right-side view of the mounting hardware shown in FIG. 11;

FIG. 17 is a top view of the mounting hardware shown in FIG. 11;

FIG. 18 is a bottom view of the mounting hardware shown in FIG. 11;

FIG. 19 is an upper perspective view of another embodiment of a mounting hardware, illustrating the mounting hardware mounted to exemplary environment;

(Continued)

FIG. 20 is another upper perspective view of the mounting hardware shown in FIG. 19;
FIG. 21 is a lower perspective view of the mounting hardware shown in FIG. 20;
FIG. 22 is a front view of the mounting hardware shown in FIG. 20;
FIG. 23 is a rear view of the mounting hardware shown in FIG. 20;
FIG. 24 is a left-side view of the mounting hardware shown in FIG. 20;
FIG. 25 is a right-side view of the mounting hardware shown in FIG. 20;
FIG. 26 is a top view of the mounting hardware shown in FIG. 20; and,
FIG. 27 is a bottom view of the mounting hardware shown in FIG. 20.
The broken lines are for the purpose of illustrating portions of the mounting hardware that form no part of the claimed design. The broken line showing of the attachment structures in FIGS. 1, 10, and 19 illustrates the environment of the claimed design and forms no part thereof.
The drawings contain symbolic breaks each defined by a pair of break lines. Portions of the mounting hardware between the break lines in each pair form no part of the claimed design.
